UNITED STATES PATENT OFFICE.

ERSKINE M. COVERT, OF SOUTH BEND, INDIANA.

FEEDING MECHANISM FOR STAMPING-PRESSES.

1,239,463.

Specification of Letters Patent. Patented Sept. 11, 1917.

Application filed June 9, 1917. Serial No. 173,729.

To all whom it may concern:

Be it known that I, ERSKINE M. COVERT, a citizen of the United States, residing in the city of South Bend, county of St. Joseph, Indiana, have invented new and useful Improvements in Feeding Mechanism for Stamping-PresSES, of which the following is a specification.

My invention relates to improvements in feeding mechanism for metal stamping presses of the inclined type wherein metal disks or plates are pressed or punched into various forms.

The principal object of my invention is the production of a device of the character described in which metal blanks, or plates, are deposited in a holder by the operator at a point remote from the stamp or punch of the press machine and immediately thereafter mechanically moved to and deposited upon the die ahead of the descending stamp, whereby all danger to the fingers and hands of the operator is eliminated.

Another object is the production of a device of the character described which permits of continuous operation of the stamping machine. Other objects of my invention will be described herein.

The preferred embodiment of my invention is well illustrated in the accompanying drawings in which Figure 1 is a side elevation of my invention showing a fragment of a stamping press to which the invention is applied; Fig. 2 is a plan view of the pan or blank holder, guideway, stop fingers and other members assembled around the pan or holder; and Fig. 3 is a plan view of the driving mechanism.

Similar numerals of reference refer to similar members and parts of members throughout the several views on the drawings.

Referring to the drawings in detail, the numerals 1 and 2 indicate substantially parallel frame bars rigidly connected by a transverse bar 3, the whole being secured at its forward end to the press frame 4 and projecting therefrom outwardly and upwardly somewhat. The numeral 5 indicates a die member carried by the press and adapted to be periodically engaged by a reciprocating stamp 6, in the usual manner, for pressing the metal blanks into form thereon.

55 The numerals 7 and 8 indicate a pair of

cooperating and parallel guide members rigidly mounted upon the transverse frame bar 3 and spaced apart to accord with the diameter of the die 5, having their forward or discharge ends arranged adjacent 60 said die. The numeral 9 indicates a shaft extending transversely of the frame members 1 and 2 and journaled at 10 and 11, respectively, in the outer ends of said frame members. The numeral 12 indicates the 65 disk or blank holder, or receiving pan, open at its forward end and which rests upon the outer ends of the guides 7 and 8, and flanged on each side and the back end thereof, said back end being provided with a pair of 70 lugs 13 and 14 which are suitably apertured at 15 and 16, respectively, for mounting the pin 17.

The numeral 18 indicates a lever revolvably mounted upon the shaft 9 beneath the pan 75 12, the hub whereof normally supports said pan, the outer end of said lever being apertured at 19 to receive the pin 17 and upon which it is mounted. The numeral 20 indicates a lever arm projecting from the 80 hub of the lever 18 the outer end of which is pivotally connected with the lever actuation rod 21 adapted to periodically oscillate said lever in a vertical plane, by means hereinafter described, for tilting the pan 85 12 and moving it forward. The numeral 22 indicates a stop finger recess formed in the floor of the pan 12 at its open end and intermediate its side flanges, and in which the point of the stop finger 23 is normally arranged, projecting above the floor of the pan to limit the forward movement, or 90 sliding tendency, of each blank as it is placed in the pan by the operator. The base of the finger 23 is rigidly fastened to the hub of the levers 18 and 20 by a screw 95 24, or otherwise, the point of said finger being adapted to be periodically retracted from the recess 22 when the levers 18 and 20 are oscillated by the actuation of the rod 100 21, as hereinafter described. The numeral 25 indicates a coil tension spring anchored to the rod 21 at 26 and fastened to the under side of the pan 12 at 27, being adapted to yieldably confine the forward end of 105 said pan upon the guides 7 and 8.

The numerals 28 and 29 indicate a pair of stop arms pivotally mounted upon the frame members at 30 and 31, respectively, and on opposite sides of the die 5, being adapted, 110

when moved into position as hereinafter described, to limit the forward movement of the blank discharged from the pan 12 and to maintain its juxtaposition upon the die 5 until the engagement thereof by the stamp 6. The numerals 32 and 33 indicate coil springs anchored on the frame members at 34 and 35, respectively, and connected with the stop arms 28 and 29 at 36 and 37, respectively, and adapted, when the arms 28 and 29 are relieved of the restraint hereinafter described, to move said arms into operative position, said position being the position of the arms shown in full or solid lines in Fig. 15 2 of the drawings. The numerals 38 and 39 indicate a pair of stop arm retraction chains, or members, connected at their outer ends with the retraction levers 40 and 41, respectively, said levers being rigidly mounted 20 upon the shaft 9 adjacent its opposite ends and connected with said stop arms at 42 and 43, respectively.

The numeral 44 indicates a lever rigidly mounted upon the shaft 9 and connected at 25 its outer end with the actuation rod 45 which is adapted to oscillate said lever, as herein-after described, thereby partially rotating said shaft for relieving the arms 28 and 29 of the restraint of the chains 38 and 39.

30 In operation, the blank to be stamped is placed in the pan or holder 12, the blank edge sliding into engagement with the stop finger 23. Normally the stop arms 28 and 29 are retracted by the chains 38 and 39, as indicated by the dotted lines of said arms in Fig. 2, and the inward movement of said stop arms is timed to occur prior to the projection of the blank from the pan 12. Closely following the inward movement of said stop arms 28 and 29 the levers 20 and 18 are oscillated by the vertical actuation of the rod 21, thereby retracting the point of the stop finger 23 from the aperture 22 and tilting the pan 12 upward and forward, whereby the 35 blank carried in said pan is projected therefrom upon the guideway 7 and 8 and thence to the die 5, being stopped and held in position upon the die by the arms 28 and 29.

The numeral 46 indicates a shaft suitably 50 mounted in the base of the press (not shown) or in any other suitable manner, and upon which are pivotally mounted the driver arms 47 and 48, the forked outer ends whereof are operatively connected with the lower ends of the rods 21 and 45, respectively. The numerals 49 and 50 indicate coil tension springs connected with the arms 47 and 48, respectively, both of which springs are anchored in a base member 51 or to the base of the press, the latter not being shown. The inner ends, or opposite extremities, of the arms 47 and 48 are arranged beneath the driver disk shaft 52 and are normally held in contact therewith by the tension of the springs 49 and 50, said

shaft being suitably journaled in the press base (not shown).

The numeral 53 indicates a driver disk, or cam pin carrier, rigidly mounted upon the shaft 52 upon the opposite lateral peripheries whereof are rigidly mounted the laterally projecting cam pins 54 and 55, respectively, arranged in different disk radial planes and adapted to be moved by the rotating disk 53 into successive engagement 75 with the arms 48 and 47, respectively, for effecting the successive depression movements thereof, whereby the levers 44, 18 and 20 are oscillated. The numeral 56 indicates a tooth clutch member rigidly mounted 80 upon one end of the shaft 52 and adapted to be engaged by the clutch member 57 which is splined upon the driving shaft 58 and adapted to be shifted back and forth thereon by any suitable shifting mechanism. The numeral 59 indicates a driving sprocket wheel rigidly mounted on the driving shaft 58 and engaged by a sprocket chain 60 operatively connected with an initial driving sprocket wheel (not shown) for transmitting power to the shaft 58. 90

From the foregoing description it is evident that the rod 45 is upwardly actuated by the cam pin 55 prior to the actuation of the arm 47 by the pin 54, thereby oscillating the lever 44 and partially rotating the shaft 9, whereby both levers 40 and 41 are oscillated toward the fingers 28 and 29 and relieving them of the tension or restraint of the chains 38 and 39. Thereupon, the exertion of the springs 32 and 33 closes the stop fingers 28 and 29 against the die 5. Immediately thereafter the cam pin 54 actuates the rod 21, whereby the levers 18 and 20 are oscillated and the stop fingers 23 moved downward and out of the pan recess 22, whereby the pan 12 is moved forward and rear end thereof upwardly tilted discharging the blank upon the guides 7 and 8. 100

When the arms 47 and 48 are relieved of the exertion of the disk pins 54 and 55 they are retracted by the springs 49 and 50, whereby the fingers 28 and 29 are retracted by the chains 38 and 39 and the pan 12 is restored to its original position with the stop finger point again projecting through the pan recess 22. Following the retraction of the fingers 28 and 29, as indicated by the dotted lines thereof in Fig. 2, the pressed and finished disk or plate is discharged from the die and forwarded, said fingers being retracted to permit of the passage of the disk in its finished state. 110

I claim:

1. The combination with a pressing machine of the class described and a guideway for delivering blanks in the path of the machine stamp, of a tiltably mounted blank holding member having one end thereof arranged adjacent said guideway; a retract- 125

130

- able finger for confining the blank in said combination with the guideway for delivering blanks in the path of the machine stamp, a movable and tilttable blank receiving pan having one end thereof slidably mounted and resiliently restrained adjacent one end of 70 said guideway; a retractable stop finger for confining the blank within the pan prior to the tilt thereof; periodically operating mechanism for tilting and forwardly projecting said pan to discharge the blank upon 75 said guideway, said mechanism including devices for retracting said stop finger to permit the discharge of the blank from said pan; and means for retracting said pan, said means including devices for restoring said 80 stop finger to the stop position.
2. The combination with a pressing machine of the class described and a guideway for delivering blanks in the path of the machine stamp, of a movably and tiltably mounted blank holding member having one end thereof arranged adjacent said guideway and adapted to be tilted and moved forward for discharging a blank upon said 85 guideway; a retractable finger for confining the blank in said holder; means for retracting said finger; means for tilting and forwardly moving said blank holder for discharging the blank therefrom upon said 90 guideway, movable stop means adapted to limit the movement of the blank and for confining it upon the machine die; means for synchronizing the stop means movements with the movements of the machine stamp; and means for retracting the blank holder after discharging the blank upon said guideway. 95
3. In a device of the class described and in combination with the guideway for delivering blanks in the path of the machine stamp, a movable and tilttable blank receiving pan having one end thereof slidably mounted adjacent one end of said guideway; a retractable stop finger for confining the blank within the pan prior to the tilt thereof; mechanism for tilting and forwardly projecting said pan to discharge the blank upon said guideway said mechanism including devices for retracting said stop finger to permit the discharge of the blank from said pan; and means for retracting said pan. 100
4. In a device of the class described and in combination with the guideway for delivering blanks in the path of the machine stamp, a movable and tilttable blank receiving pan having one end thereof slidably mounted adjacent one end of said guideway; a retractable stop finger for confining the blank within the pan prior to the tilt thereof; periodically operating mechanism for tilting and forwardly projecting said pan to discharge the blank upon said guideway, said mechanism including devices for retracting said stop finger to permit the discharge of the blank from said pan; and resilient means for retracting said pan, said pan retracting means being coöperative with means for confining the forward end of said pan upon its mount. 105
5. In a device of the class described and in 110
6. In a device of the class described and in combination with the guideway for delivering blanks in the path of the machine stamp, a blank receiving pan having one end thereof slidably mounted upon one end of said guideway and having its opposite end carried by an oscillatory lever adapted to be oscillated in a vertical plane for tilting and forwardly projecting said pan; periodically operating means connected with said lever for oscillating it in a vertical plane; spring actuated means for effecting a retraction of said lever, and thereby said pan; and resilient means connected with said pan for 115 confining it upon said guideway. 120
7. In a device of the class described and in combination with the guideway for delivering blanks in the path of the machine stamp, an inclined blank receiving pan having one end thereof slidably mounted upon said guideway and having its other end carried by an oscillatory lever adapted to be oscillated in a vertical plane for tilting and forwardly projecting said pan; means for resiliently confining said pan upon said guideway; a stop finger having one end thereof carried by said lever and its outer end projecting above the floor of said pan, said finger being movable with said lever; periodically operating means connected with said lever for oscillating it in a vertical plane; and means for retracting said lever, and thereby said pan. 125
8. In a device of the class described and in combination with the guideway for delivering blanks in the path of the machine stamp, a blank receiving pan having one end thereof slidably mounted adjacent one end of said guideway and having its other end carried by an oscillatory lever adapted to be oscillated in a vertical plane for tilting and forwardly projecting said pan; periodically operating means for oscillating said lever said means comprising an arm connected with said lever, a rod connected with said arm, a lever arm pivotally mounted intermediate its extremities and operatively connected at one end with said rod, and a rotary cam member periodically engaging 130

the lever arm for depressing it; and means for retracting said oscillatory lever, and thereby said pan.

9. In a device of the class described and 5 in combination with the guideway for delivering blanks in the path of the machine stamp, a blank receiving pan having one end thereof slidably mounted adjacent one end of said guideway and having its other end 10 carried by an oscillatory lever adapted to be oscillated in a vertical plane for tilting and forwardly projecting said pan; periodically operating means for oscillating said

lever said means comprising an arm connected with said lever, a rod connected with 15 said arm, a lever arm pivotally mounted intermediate its extremities and operatively connected at one end with said rod, and a rotary cam member periodically engaging the lever arm for depressing it; and resilient 20 means connected with said lever arm for retracting it, and thereby said oscillatory lever and said pan.

In testimony whereof I have hereunto affixed my signature this 2d day of June, 1917. 25

ERSKINE M. COVERT.
